(57) **CLAIM**

The ornamental design for a roof for power conditioning subsystem, as shown and described.

DESCRIPTION

FIG. 1 is a perspective view viewed from a top side of a roof for power conditioning subsystem showing our new design; FIG. 2 is a perspective view viewed from a bottom side thereof;

FIG. 3 is a front elevation view thereof;

FIG. 4 is a rear elevation view thereof;

FIG. 5 is a right side elevation view thereof; the left side elevation view being a mirror image thereof;

FIG. 6 is a top plan view thereof;

FIG. 7 is a bottom plan view thereof;

FIG. 8 is a sectional view taken along line 8-8 in FIG. 3;

FIG. 9 is a sectional view taken along line 9-9 in FIG. 6;

FIG. 10 is an enlarged view taken along line 10-10 in FIG. 8; FIG. 11 is an enlarged view taken along line 11-11 in FIG. 8; FIG. 12 is an enlarged view taken along lines 12-12 and 12'-12' in FIG. 9;

FIG. 13 is an enlarged view taken along line 13-13 in FIG. 9; FIG. 14 is a perspective view showing our claimed design in a position of use; and,

FIG. 15 is another perspective view showing our claimed design in a position of use.

The portions of the drawings in broken lines are environment and the elements depicted in broken lines form no part of the claimed design.

1 Claim, 7 Drawing Sheets

UNITED STATES PATENT AND TRADEMARK OFFICE
CERTIFICATE OF CORRECTION

PATENT NO. : D746,424 S
APPLICATION NO. : 29/485599
DATED : December 29, 2015
INVENTOR(S) : Nobuhiro Takahashi et al.

Page 1 of 1

It is certified that error appears in the above-identified patent and that said Letters Patent is hereby corrected as shown below:

Title Page, item (73) the assignee information should be corrected to read as follows:

Assignee:

Rubber Co., LTD, Nagoya-City, Aichi (JP)

Signed and Sealed this
Tenth Day of May, 2016

Michelle K. Lee
Director of the United States Patent and Trademark Office
